UNITED STATES PATENT OFFICE.

MERLIN Y. CHARLES, OF WICHITA, KANSAS.

REINFORCED HOLLOW CONCRETE WALL.

1,420,521.

Specification of Letters Patent. Patented June 20, 1922.

Application filed January 18, 1921. Serial No. 438,103.

To all whom it may concern:

Be it known that I, MERLIN Y. CHARLES, a citizen of the United States, and a resident of Wichita, in the county of Sedgwick and State of Kansas, have invented certain new and useful Improvements in Reinforced Hollow Concrete Walls, of which the following is a specification.

My invention relates to that class of concrete walls, composed of small slabs of concrete that can be assembled by unskilled labor.

The object of my invention is to construct a wall having an air space to insure against dampness passing through from one side to the other, and also simple means for reinforcing with steel rods and means for spacing the wall to a uniform thickness.

Another object of my invention is to provide a simple and effective means by the use of the projecting ends of the wall bonds to act as a screed, requiring certain thickness of interior or exterior plaster.

A further object of my improvement is to provide a continuous reinforced column of concrete functioning as joist bearings, and means for stiffening the wall vertically, also means for applying a horizontal reinforcing rod applicable to the wall construction in general and more especially to reinforce a beam over openings in the wall, and without additional forms.

Also means for placing metallic bonds when said wall is to be veneered with brick, stone, terra cotta, or other materials.

I attain these objects by the mechanism illustrated in the accompanying drawings, in which—

Fig. 1 is a fragmentary perspective view of a wall showing corner construction, reinforcing and general assembly of the parts. Fig. 2 is a perspective view of one of the slabs. Fig. 3 is a perspective view of one of the bond blocks. Fig. 4 is a sectional detail view through bond block at the reinforcing rod, taken on line A in Fig. 3.

Fig. 2 shows one of the precast concrete slabs as employed in erecting the longitudinal wall elements. The slab 1 is relatively thin in width and of greater length than depth, the opposite corners along one edge being cut away as disclosed and the respective vertical end elements thereof fashioned concave as seen at 3 and convex as seen at 6; this leaves end elements on the other edge, longitudinally extending beyond the end ele-

ments previously mentioned which are likewise concave at 3 and convex at 6 but in reverse position to the other end elements 3 and 6 of the slab. The concave 3 is adapted to receive the convex member 4 of the bond block and the concave 5 is adapted to receive the convex ends 6, by this means when the ends of slab 1 are tightly jambed together with the bond blocks 7 interposed between the ends of said slabs as shown in Fig. 5, will prevent the slab members 1 from spreading during the course of construction by reason of the concave and convex interlocking feature, and said bond blocks being inverted alternately will form a continuous head for the formation of a column as shown at 9 in which reinforcing rods 10 will be placed and concrete poured as shown at 11, which applies to all of the shafts formed by the bond blocks 7, and said concrete will firmly unite the members adjacent thereto. D is a notch formed to receive a metal bond E without separating the slabs 1 said bonds protrude into the concrete shafts 11 extending outward between the joints F of the veneered masonry, by which means the veneering is firmly bonded to the wall.

In Fig. 1 a portion of the wall is removed at which place is shown the bond block 7 with the curved wing members down, and at C the bond block is inverted, the object of which will be hereinafter explained.

The bond block 7 is molded of concrete, the center of which is rectangular in shape and has protruding members 12 the sides of which are convex and concave as shown at 4 and 5, the height of the block 7 corresponds to the depth of the slab 1, while the height of each of the side members 12 beginning from the base of the said block 7 is equivalent to the depth of the cut away corner portions of the slab 1 shown in Fig. 2, and by which medium the ends of slabs 1 are bonded together in parallel alignment, and in conjunction with said members the protruding square end 13 of said block functions as a separator for said slabs, and said members also contacts the opposite end of the adjacent bond block as they build up through the wall forming a vertical enclosure 9 as heretofore described.

The bond block 7 has semi-circular grooves 14 in each end of sufficient size for a reinforcing rod 15 to pass through without separating the blocks. 16 is a reinforcing rod, one more of which are inserted to strengthen

the protruding members 12 by which means slabs 1 are safely bonded together.

When said walls are completed they may be plastered on the inside, and veneered with 5 brick, stone, or other materials, or stuccoed on the exterior, and the application of stucco and interior plastering shall be in thickness equal to or greater than the protruding ends G of the bond blocks, said ends protrude 10 past the surface of the wall blocks 1 as shown by dotted line 23 in Fig. 4.

Modifications may be made as lies within the scope of appended claims.

Having described my invention, I claim 15 and desire to secure by Letters Patent:

1. In a wall construction, the combination of a plurality of slabs, longitudinally extending, superposed in spaced vertical planes; the slabs in one vertical plane being arranged also in horizontal courses with a slab 20 of like character immediately opposite it in the other vertical plane; each slab being greater in length than the depth with the opposite corners along one edge removed; 25 the slabs in a longitudinal course being alternately reversed in position, vertically and in abutting relationship along the longitudinal edges of their projecting end portions; and a plurality of bond blocks, superposed in alternating reversed position and in spaced vertical planes, transversely arranged intermediate said longitudinal slabs; said blocks having a central section equivalent in width to the spaced distance between the 30 vertical longitudinal slab courses and with wing portions outwardly projecting there- 35

from and arranged intermediate the adjacent ends of the contiguous slab members.

2. In a wall construction, the combination of a plurality of slabs, longitudinally extending, superposed in spaced vertical planes; the slabs in one vertical plane being arranged also in horizontal courses with a slab of like character immediately opposite it in the other vertical plane; each slab being 40 greater in length than in depth with the opposite corners along one edge cut away and the respective ends thereof formed concave and convex but in reverse order; the slabs in a longitudinal course being alternately reversed in position, vertically, and in abutting relationship along the longitudinal edges of their projecting end portions; and a plurality of bond blocks, superposed in alternating reversed position and in spaced vertical 45 planes, transversely arranged intermediate the longitudinal slabs; said blocks having a central section equivalent in width to the spaced distance between the vertical slab courses and with wing portions outwardly 50 projecting therefrom and arranged intermediate the adjacent ends of the contiguous slab members and extending beyond said slabs; and concave and convex faces on said blocks membering with the convex and concave portions of said slabs, substantially as specified.

MERLIN Y. CHARLES.
